UNITED STATES PATENT OFFICE.

EDGAR F. WAIT, OF AKRON, OHIO.

DESIGN FOR A TIRE.

Application filed March 1, 1924. Serial No. 8,799. Term of patent 14 years.

To all whom it may concern:

Be it known that I, EDGAR F. WAIT, a citizen of the United States, residing at Akron, in the county of Summit and State of Ohio, have invented a new, original, and ornamental Design for Tires, of which the following is a specification, reference being had to the accompanying drawings, forming a part thereof.

Figure 1 is a plan view of a portion of a tire showing my improved design, and,

I claim:

The ornamental design for a tire as shown.
